OIL WELL HEATER

James R. Vandever, Pampa, Tex., assignor to
Richard P. Abele, as trustee, Tulsa, Okla.

Application November 2, 1934, Serial No. 751,215

6 Claims. (Cl. 166—17)

This invention relates to heaters for oil wells. It is of that general type of heater which is adapted to be lowered into an oil well for the purpose of heating the oil producing strata of the well to melt the paraffine and other solidified petroleum products which clog the oil producing formation.

In general, the improved heater is of that class of heaters which employ chemicals which, when mixed, will produce an exothermic reaction as a source of heat. This invention provides a heater of this type which carries within it the chemicals required to produce the desired reaction, and which has means for bringing such chemicals into contact with each other when the heater has been lowered to the bottom of the well.

A further feature of the invention consists in the internal design of heaters of this type whereby the substances which produce the reaction may be completely and thoroughly brought into contact with one another to produce a complete reaction with the maximum of efficiency and least possible waste of chemical.

Still another feature of the invention consists in the provision of escape valves in combination with the improved heater which prevent the escape of a portion of the vapors resulting from the reaction and serve to maintain the pressure within the housing at a predetermined maximum during the reaction.

Yet another feature of the invention consists in the provision of improved means for bringing the substances carried within the heater into contact with each other.

Yet another feature of the invention consists in the provision of means for conducting gases and vapors resulting from the reaction from the lower portion of the heater to substantially the upper end thereof in order that the movement of these gases will not interfere with the downward movement of the fluid causing the reaction.

Many other and further objects and advantages of the invention will become apparent from the following specification when considered in connection with the accompanying drawing.

In the drawing:

Figure 1 is a side elevation of the improved heater;

Figure 2 is a vertical sectional view of the heater showing the improved arrangement of parts interiorly thereof; and

Figure 3 is a vertical sectional view of a modified form of the heater.

With more particular reference to the drawing, the improved heater comprises a housing 1 preferably cylindrical in form tightly closed at its lower end by a transverse wall 2 and tapered at its upper end to form a neck 3 which may be closed by a suitable filler cap 4. The housing is preferably made of two sections 1^a and 1^b, which are joined together by means of a coupling 5. A partition wall 6 is located internally of the heater and serves to divide the heater internally into two fluid tight chambers 7 and 8.

The partition wall 6 is held in position by means of the coupling 5 and the ends of the sections 1^a and 1^b of the housing which are screwed into the coupling 5. Annular gaskets 9 may be placed upon the upper and lower sides of the partition wall 6 in order to insure a fluid tight joint. The lower chamber of the heater is provided with a centrally disposed cylindrical pipe 10 mounted axially therein of considerably less diameter than the housing, and having its upper end reaching substantially to the partition wall 6 separating the two chambers.

This pipe 10 has a plurality of perforations 11 therein substantially throughout its length, although the upper portion thereof is preferably imperforate. The pipe 10 is maintained in an axial central position of the lower chamber by means of a removable annular perforated disc 12, which has a central aperture sufficiently large to slide freely over the pipe 10 and an outer diameter sufficiently small to slip within the housing section 1^b. The disc 12 is maintained in a position about midway of the pipe 10 by means of a plurality of lugs 13 struck up from the surface of the pipe 10. The disc 12 has a plurality of escape holes 12^a therethrough. The upper portion of the housing 1^a is provided with a pair of escape valves 14, which control the escape of vapors and gases from the interior of the housing.

These escape valves 14 preferably comprise a cage 15 rigidly secured to the housing and having a ball 17 adapted to engage a valve seat 18 ground into the housing proper. The ball 17 is pressed into engagement with its seat by means of a coil spring 19 confined between the ball 17 and a set screw 20 threadably mounted in the cage 15.

It may be seen from the foregoing that the escape valve may thus be regulated to control the maximum pressure which may be permitted to exist within the housing. An aperture 21 is provided in the partition wall 6 and has threaded into it a relatively long gas escape pipe 22, which extends to the upper portion of the chamber 7.

Centrally of the partition wall 6 is an aperture ground to form a valve seat 23 for a valve 24. The valve 24 has a stem 25 which extends downwardly centrally of the pipe 10. The valve stem

5 25 is connected by means of a resilient connection 26 to a valve operating rod 27, which extends through an aperture 28 in the central portion of the bottom 2 of the casing. Both the upper and lower portions of this aperture are ground to form 10 valve seats, and a pair of spaced valve members 29^a and 29^b are secured to the valve operating rod 27 to engage these valve seats.

The lower portion of the valve rod is flared to form an inverted cup 30 which when brought into 15 engagement with the bottom of the well will serve to actuate the valve.

A bail or support 31 is secured to the upper portion of the housing to provide means by which the heater may be lowered into the well. The operation 20 of the above described apparatus is preferably substantially as follows.

The lower portion of the annular space between the wall 1^b of the housing and the perforated pipe 10 is filled with a mixture of caustic 25 soda and aluminum filings or other heat producing substances. The partition plate 12 is then slid down over the pipe 10 until it rests upon the top of the material in the annular space or upon the lugs 13. The heater is then assembled and 30 supported by means of the bail 31.

The weight of the valve 24 and associated parts will serve to maintain this valve against its seat 33. The upper chamber 7 of the heater housing is then filled with water up to a point substantially 35 below the end of the pipe 22. The heater is then charged ready for use and may be lowered into the well by means of any suitable rope or cable secured to the bail 31.

Upon reaching the bottom of the well, the valve 40 operating rod 27 will be raised relative to the heater housing due to the fact that the flared out portion 30 thereof abuts against the bottom of the well. This will serve to open the valve 24 and permit the water in the chamber 7 to descend 45 downwardly within the pipe 10.

It will also be seen that the valve body 29^b serves to maintain the lower chamber tightly closed thus preventing the escape of any substantial amount of fluid either into or out from the 50 housing.

This water will gradually pass outwardly through the holes 11 in the pipe 10 and be brought into an intimate contact with the caustic soda and aluminum filings in the annular space surrounding the pipe 10. It will be apparent from the above described construction that a maximum surface area is exposed to the water consequently insuring a complete reaction.

Considerable heat will be generated as result of 60 this reaction and considerable gas and steam produced. This gas and steam is permitted to escape into the upper chamber of the heater by means of the pipe 22 and is carried sufficiently far into the upper chamber so that it will not 65 interfere with the downward movement of the water.

After the heater has rested on the bottom of the well sufficiently long to permit fluid in the upper chamber to drain into the lower chamber, 70 the heater is raised slightly from the bottom of the well sufficient to permit the valves 24 and 28 to seat against their respective seats.

As the reaction takes place, considerable pressure will be generated in the heater, increasing 75 the temperature thereof. When the pressure

within the heater has reached a predetermined maximum, the surplus gas will be permitted to escape through the escape valves 14 described above.

As is apparent from the construction of these 5 valves, the predetermined pressure within the heater may be adjusted at will to a point of maximum efficiency for the particular conditions under which the heater is being used. It is apparent that after the reaction has been completed, the 10 heater may be withdrawn from the well and recharged for subsequent similar operations.

In the modified form of the heater shown in Figure 3, a frangible seal 32 secured by screws 33 to the partition 6 is substituted for the valve 24. 15 In order to insure a fluid tight engagement of the seal in the partition walls, a gasket 34 may be interposed therebetween. A cylindrical guide pipe 35 is secured rigidly to the partition wall 6 and extends downwardly internally of the pipe 10. 20

A piercer member 36 has the lower portion 37 thereof flared out to engage the bottom of the hole and has a cylindrical stem passing through a packing gland 38 in the bottom wall of the heater housing. A collar 39 is secured to the stem of the piercer member above the packing gland in order to limit the movement of the piercer member.

The upper end of the piercer member is pointed at 40 and lies normally just beneath the seal 32. It will be apparent in this construction that when the heater is lowered into the well, the lowering movement of the heater relative to the piercer member will cause a piercing of the seal 32, thus permitting the fluid in the upper chamber 35 to descend within the pipe 10.

The pipe 35 serves to conduct the fluid directly from the point where the seal is pierced into the pipe 10 and also serves as a guide for the point 38 of the piercer. In this modification, it will be 40 apparent as soon as the seal 32 is pierced, the heater may be raised from the bottom of the well slightly to withdraw the point of the piercer from the seal and permit a freer flow of fluid into the lower chamber. In other respects, the 45 construction and the operation of the modified form of the invention shown in Figure 5 is substantially the same as that described in connection with the form of the invention illustrated in Figure 2.

It will be apparent from the foregoing that the double valve arrangement illustrated for use in connection with the bottom wall of the heater may be equally satisfactorily employed in connection with the modification shown in Figure 3, and likewise a packing gland may equally well be substituted for the double valve arrangement shown in Figure 2.

It will further be apparent that many other 60 and further modifications of the invention will be apparent to those skilled in the art.

I claim:

1. A heater for oil wells comprising a housing adapted to be lowered into a well to be heated, 65 said housing being divided into separate upper and lower chambers, a valve for controlling the downward movement of fluid from said upper chamber into said lower chamber, means having a portion adapted to engage the bottom of said 70 well for operating said valve, and means in addition to said valve for conducting gas generated in said lower chamber to the upper portion of said upper chamber.

2. A heater for oil wells comprising a housing 75

adapted to be lowered into a well to be heated, said housing being divided internally into separate upper and lower chambers, an axially extending perforated tube in said lower chamber, 5 a valve adjacent the upper end of said tube, and means adapted to engage the bottom of said well and extending through said tube for actuating said valve.

3. A heater for oil wells comprising a housing 10 adapted to be lowered into a well to be heated, a pair of separate upper and lower chambers internally of said heater, a perforated pipe forming an axially disposed passageway through said lower chamber, means for controlling flow of 15 fluid from the upper chamber into said passageway comprising a valve located adjacent the upper end of said tube, and means adapted to engage the bottom of said well extending through said passageway for operating said valve.

20 4. A heater for oil wells comprising a housing adapted to be lowered into a well to be heated, said housing being divided internally into separate upper and lower chambers, a frangible seal normally controlling communication between 25 said chambers, a perforated tube extending axially through said lower chamber and having its upper end terminating adjacent said seal, and means for rupturing said seal comprising a rod

extending through said tube and having a portion adapted to engage the bottom of the well.

5. A heater for oil wells comprising a housing adapted to be lowered into a well to be heated, said housing being divided internally into separate upper and lower chambers, a frangible seal normally controlling communication between said chambers, a perforated tube extending axially through said lower chamber and having its upper end terminating adjacent said seal, and means for rupturing said seal comprising a rod having one end adapted to rupture said seal and the other end adapted to engage the bottom of said well, said rod extending through a packing gland in the bottom of said housing. 10 15

6. A heater for oil wells comprising a housing adapted to be lowered into an oil well to be heated, said housing being divided internally into separate upper and lower chambers, means between said chambers for controlling communication therebetween, a perforated annular wall within said lower chamber forming an axially disposed passageway therethrough and means adapted to engage the bottom of the well extending through said axially disposed passageway for 20 actuating said means for controlling communication between said chambers. 25

JAMES R. VANDEVER.
